UNITED STATES PATENT OFFICE.

CHARLES K. OLSON, OF CHICAGO, ILLINOIS.

CURTAIN-STRETCHER.

1,320,409.

Specification of Letters Patent.

Patented Nov. 4, 1919.

Application filed August 6, 1919. Serial No. 315,671.

To all whom it may concern:

Be it known that I, CHARLES K. OLSON, a citizen of the United States, residing at Chicago, in the county of Cook and State 5 of Illinois, have invented certain new and useful Improvements in Curtain-Stretchers, of which the following is a specification.

My invention relates to curtain stretchers, and has for one of its objects the provision of a simple and efficient curtain stretcher which is adapted to stand by itself unsupported and to hold the curtains so as to be engaged by a maximum amount of air.

15 A further object is the provision of a simple and efficient curtain stretcher adapted for adjustment for holding various sizes of curtains, and the like.

20 A still further object is the provision of a curtain stretcher which may be quickly and easily folded into compact form and be easily and quickly erected for use.

Other objects will appear hereinafter.

An embodiment of my invention is illustrated in the accompanying drawing, forming a part of this specification, and in which—

Figure 1 is a plan view of a curtain stretcher embodying my invention;

30 Fig. 2 is a side elevation of the same; and

Fig. 3 is an end view of two bars disposed together as when the device is folded.

In the drawing I have illustrated my invention as being triangular in horizontal cross-section, but it will be understood that the device may be formed in such a manner as to have as many sides as desirable. Also, it may be made of various materials. However, I find wood makes a very light and strong frame.

In the form illustrated I have indicated three upright corner posts 5, one of which is provided with a vertical line of points 6 to which the end of a curtain, or the like, is to be fastened in using the device. The posts 5 are preferably substantially parallel and equidistant from a center line, although, if desired, other arrangements of the posts 50 may be had.

At each side of the device I provide a plurality of strings, cords, or other flexible members 7 which extend substantially horizontally between the adjacent edges of the posts. These strings, or the like, may be secured to the posts in any desirable man-

ner. Also, at each side of the device I provide two strings, or other flexible elements 8 arranged crossing each other so as to serve as braces for the device when the latter is erected for use. The strings 8 may also be secured to the posts in any desirable manner.

The side of each of the posts 5 facing the center of the device is preferably provided with a plurality of notches 9, and in certain of said notches are disposed the ends of bars 10 arranged horizontally to provide supporting means for the side edges of the curtain, or the like. Each of the bars 10 is provided with a line of points 11 for engaging the curtain, or other article to be dried on the device. The points 11 in the upper bars 10 are preferably adjacent the lower edge thereof, and the points 11 in the lower bars 10 are preferably adjacent the upper edges thereof so that a minimum amount of space behind the curtain, or the like, will be cut off by such bars. Also, when the device is folded the bars 10 are arranged as indicated in Fig. 3 with their points 11 disposed substantially as indicated so as to prevent the points from engaging articles with which the bars might come in contact with. Also, to protect the points against injury to persons handling them. The other end of the curtain, or the like, is engaged on points 12 of an upright member 13 which may be disposed anywhere around the device against the bars 10. The bar 13 may be held against the bars 10 in any desirable manner, such as by the clamps 14. The points in bar 13 are preferably near one edge so that when the device is folded it can be placed so as to protect the 95 points 6 on one of the posts 5 in a manner similar to that indicated in Fig. 3. Extending radially from the center of the device are a plurality of links or brace members 15 each pivoted as at 16 to one of the 100 corner posts. The adjacent ends of the bars 15 are connected together in a suitable manner so that they can be easily and quickly swung on their pivotal points 16. I have indicated a rigid bar 17 pivoted as 105 at 18 to each of the bars 15, but it will be apparent that the member 17 may be any other desirable connection between the adjacent ends of the bars 15. The arrangement is such that upon pressing downwardly on 110 the bar 17 the links 15 will draw the posts up against said bar 17 when the bars 11 have

- been removed from the notches 9, and that said bars 15 and connecting members 17 will brace the posts 5 out tight against the strings 7 when the device is erected. A string 19 may be provided between one of the bars 15 and the bar 17 to limit the movement of said bar in an upward direction, thereby locking the device in the position indicated in the drawing. The top strings 7 may be connected by strings 20 with the top of member 17 so as to help draw in the top strings 7 when the device is to be folded, thereby helping to keep the strings from becoming snarled.
- It will be apparent that the upper bars 10 may be placed in the different notches 9 at the tops of the posts and the bar 13 arranged at different distances from the post having points 6 so as to accommodate various sizes of curtains. It will also be apparent that the device may be utilized for drying other articles than curtains, such as blankets or clothing, or the device may be used as a clothes-rack.
- I claim:
1. A curtain stretcher comprising a plurality of upright posts disposed about and substantially parallel with a central line; a member at said central line; a plurality of links connecting the posts with said center member; and a plurality of flexible members connecting said posts together.
  2. A curtain stretcher comprising a plurality of upright posts disposed substantially equidistant from a center line; rigid links pressing radially from said center line

on said posts; and cords fastened to the posts and limiting the movements of the latter from each other.

3. A curtain stretcher comprising a center member; a plurality of corner posts disposed about said center member; links disposed substantially radially from the center member and pivotally connected with the latter and said posts; and a plurality of flexible members connecting the posts at each vertical side of the device, some of the flexible members being arranged to act as braces.

4. A curtain stretcher comprising a plurality of upright posts having a plurality of notches therein; a plurality of bars having their ends engaging said notches; strings connecting the upright posts together; a center member; and links extending substantially radially from the center member and connecting the latter and the upright posts.

5. A curtain stretcher comprising a plurality of upright posts disposed substantially parallel; a member disposed substantially parallel and centrally of said posts; a plurality of links connecting the posts with said center member; a plurality of cords connecting the posts together; and a flexible member connected with one of the links and said center member limiting the swinging of the links in one direction.

In testimony whereof I have signed my name to this specification on this 2nd day 70 of August, A. D. 1919.

CHARLES K. OLSON.
